UNITED STATES PATENT OFFICE.

FRANCIS W. SULLIVAN, OF LOS ANGELES, CALIFORNIA.

VALVE ACTION FOR ORGANS AND THE LIKE.

Application filed February 4, 1926. Serial No. 85,846.

This invention relates to valve actions and more especially to electrically-operated valve actions of the type used, for example, in the modern pipe organ controlled electrically from the console.

Among the important requirements to be considered, in the building of valves of this type, are quick action of the valve, a relatively large flow of air through the valve at the instant of opening and low cost of manufacture, and an object of this invention is to produce a valve action conforming to these requirements.

A high degree of responsiveness of the valve action is necessary in order to perfectly respond to the organist's touch on the keys of the console. The attainment of a relatively large flow of air through the valve at the instant of opening is highly important in order to avoid a puffing effect and produce an even tone for, if a smaller flow of air passed by the valve first sounds the note and then the flow is largely augmented while the note is sounding, the puffing effect will be noticeable in the note. This invention avoids these objections in a high degree.

Other objects and advantages will appear in the subjoined detailed description.

The accompanying drawings illustrate the invention.

Figure 1 is an elevation, mainly in section, of a valve action constructed in accordance with the provisions of this invention.

Figure 2 is an elevation, partly in section, from the line indicated by 2-2, Fig. 1.

Figure 3 is a fragmental elevation, partly in section, from the line indicated by 3-3, Fig. 1.

Figure 4 is an enlarged plan view, partly in section, from the line indicated by 4-4, Fig. 1.

Figure 5 is a bottom view of Fig. 4.

Figure 6 is a perspective view of the electrically-operated valve.

Figure 7 is a perspective view of the electrically-operated valve unit complete ready for assembling with the air chest.

An air chest 11 is indicated in vertical section in Fig. 1 and said chest may be made as long as desired so as to accommodate whatever number of pipes it is intended to operate from said chest. Only a very short section of the chest 11 is indicated in Fig. 2. Air is admitted to the chest 11 from a suitable source of compressed air supply through an intake port 12 in one of the end walls 13

of said chest, the other end wall not being shown in the drawings, owing to the nature of the views, as this construction is well understood in this art.

60

A transverse duct 14 is provided in the top wall 15 of the chest and opening from said duct to the interior of the chest is an elongate outlet port 16 controlled by an elongate flap valve 17 which is hinged in the chest and is exposed to the air pressure in the chest. Opening upwardly from the duct 14 is an outlet port 18 adapted to communicate with the lower end of the pipe, not shown, that is to receive air through said port. The port 16 is of much greater area than the port 18 as is customary.

70

The flap valve 17 is controlled by a hinge-type air bellows 19 which may be of any desired or approved construction, there being an L-shaped arm 20 connecting the bellows with the flap valve 17. The arm 20 projects from the hinge end of the bellows so that said arm together with one of the side members of the bellows forms a bell-crank lever, thus enabling the arm 20 to be applied in such manner to the valve 17 that the plane of operation of said valve is normal to the plane of operation of the bellows for a reason to appear hereinafter. A

75

spring 21 tends to hold the flap valve 17 closed. Air is admitted to the interior of the bellows 19 through a duct 22 formed partially in one of the side walls 23 of the chest and partially in the bottom 24 of said chest. The bellows 19 is exposed externally to the air pressure in the chest and it will now appear that, upon the bellows 19 being subjected to equal pressures within and without, the flap valve 17 will be closed by pressure of the spring 21. When, however, air is exhausted from the bellows 19 through the duct 22, the air pressure within the air chest will collapse said bellows, thus operating the arm 20 to open the flap valve.

80

The outer end of the arm 20 bears upon the upper face of a shoulder 25 that projects from the front edge of the flap valve 17. It is to be noted that the flap valve 17 is hinged at 251 to the top wall 15 along one of the longitudinal edges of said flap valve, as indicated at 26, and that, in consequence, said flap valve in opening and closing swings through an arc that lies in a plane extending transversely of the flap valve. The advantage of this is that, when the flap valve opens to even a slight degree, the flap valve

90

95

100

105

110

115

will be spaced along one longitudinal edge thereof from the top wall 15 equally from end to end of the flap valve, thus admitting at the instant of opening of the valve a 5 larger flow of air through the port 16 than if the flap valve were hinged at one end for, in that event, at the instant of opening of the valve the air would only be admitted uniformly at one end of the flap valve. 10 Also, the flap valve travels through a shorter arc in its opening and closing movement by being hinged along one longitudinal edge than if it were hinged at one end and thus a given degree of movement of the bellows 15 produces greater movement of the free longitudinal edge of the flap valve than it would of the free end of said valve if said valve were hinged at one end.

A means will now be described for alternately admitting air to and exhausting air from the bellows. The duct 22 communicates through a port 27 with the interior of the chest 11, and said port is controlled by a valve plug 28, the opening movement of 25 which is limited by a stop 29 fixed at one end in the bottom 24. The valve 28, when open, admits compressed air from the chest to the duct 22 to expand the bellows and thus hold the flap valve 17 closed. These 30 are the normal positions of the flap valve 17 and valve plug 28.

In order to cause the bellows 19 to collapse to open the valve 17, it is necessary to close the valve plug 28 and exhaust air 35 from the duct 22, and such exhaust is accomplished through a port 30 controlled by a diaphragm valve 31. When the valve 31 is open, air exhausts from the duct 22 through the port 30 to the atmosphere. The 40 diaphragm valve 31 rests against the lower end of a valve stem 48 which connects with the valve plug 28 so that closing movement of the valve 31 will initiate opening movement of the valve plug 28.

The diaphragm valve 31 constitutes a part 45 of an electrically-operated valve unit which is indicated in general by the character 32, said unit being shown intact in Fig. 7 of the drawings. This unit is otherwise constructed as follows: The diaphragm valve 31, of thin leather or the like, is secured at 50 its edges to a body formed, in this instance, by upper and lower plates 33, 34, respectively. The diaphragm valve extends across 55 and closes an opening 35 in the plate 33 and is clamped at its edges between the plates 33, 34. The lower plate 34 is recessed so as to form between said plates an air passage 36 and those portions of the diaphragm 60 valve that are clamped between the plates form an air-tight packing for the joint between the plates. One end of the air passage 36 communicates with a valve chamber 37 formed by recessing the bottom plate 34, 65 and in said chamber is a disc valve 38 adapt-

ed in its lower position to close a port 39 formed in the bottom plate 34. The valve 38, in this instance, constitutes an armature as the upper face thereof is made of magnetic metal 40 which is attracted upwardly, 70 to open the port 39, by an electro-magnet 41 riveted or otherwise secured to the upper plate 33 and positioned to effect upward movement of the valve 38. When the unit 32 is in place, the electro-magnet 41 is accommodated in an opening 42 which leads from the interior of the valve chest through the bottom wall 24 and through a packing member 43 of felt or other suitable material which lies between the bottom wall 24 80 and the upper plate 33. The opening 42 constitutes an air passage or duct. In its upper position the valve 38 closes a port or ports 44 formed in the upper plate 33, said ports communicating the valve chamber 85 37 with the passage 42.

The unit 32 is releasably attached in place by any suitable means and, in this instance, said means at one end being a screw 45 passing through a slot 49 in one end of each of the plates 33, 34 and into the bottom 24; and said means at the other end being a spring latch 46 secured by a screw 47 to the bottom 24. Thus for repair or replacement of the unit 32, the latch 46 will be sprung 95 and the unit will then be moved to the left in Fig. 1 to bring the slots 36 out of registration with the screw 45. The opening 42 is made sufficiently large to accommodate this movement. 100

The parts being in the positions shown in Fig. 1, the operation of the invention is as follows: With the parts in the position shown, the air pressures in the interior of the chest and in the duct 22 will be equalized, and thus the spring 21 will hold the valve 17 closed. Now assume that the electro-magnet 41 is energized, in the manner well understood in this art, by operation of one of the keys of the console. Upon such energization of the electro-magnet 41, the valve 38 will be operated by said electro-magnet to close the ports 44 so as to shut off from the air passage 36 the air pressure of the air chest. This movement of the valve 38 will cause it to uncover the port 39 so as to exhaust air from the air passage 36 to the atmosphere. The greater pressure within the duct 22 will then operate to instantly collapse the diaphragm valve 31, thus reducing the pressure in the duct 22, whereupon the greater pressure in the air chest will close the valve 28 and collapse the bellows 19 which operates to open the valve 17, thus permitting air to flow from the air chest through the port 16, duct 14 and port 18 into the pipe, not shown, that is to be provided with air by energization of the electromagnet. 115

As soon as the key at the console is re- 130

leased, thus de-energizing the electro-magnet 41, the valve 38 will be operated by gravity to close the port 39 and open the ports 44, thereby restoring relatively high air pressure beneath the diaphragm valve 31 so as to cause said diaphragm valve to close the port 30 and open the valve 28. It will be noted that the effective area of the valve 31 is greater than that of the valve plug 28, so that equal air pressures in the passage 36 and within the air chest will effect closure of the valve 31 and opening of the valve 28. Upon thus opening the valve 28, air passes from the air chest into the duct 22 to expand the bellows 19, thus closing the valve 17 so as to shut off air from the pipe.

One of the valve actions employed very largely at the present time employs four valves and two bellows to accomplish what I accomplish with four valves and one bellows, and thus I attain a simplified construction without loss of the great advantages due to the use of a bellows-operated main valve, said main valve being the one that admits the air to the pipe. The particular advantage of employing a bellows-operated valve is quick and sensitive action and relatively great movement. Thus, with the use of a bellows-operated main valve, a relatively small and cheaply constructed electro-

magnet may be used with a relatively low electric current consumption.

I claim:

1. A valve action of the character described comprising a body having an air passage and having an opening and a valve chamber communicating with the passage, a diaphragm valve closing said opening, there being ports in opposite sides of the valve chamber, a second valve in the valve chamber between said ports formed at least in part of a magnetic metal, and an electro-magnet positioned to effect movement of the second valve to open and close the ports. 40

2. A valve action of the character described comprising two plates providing an intercommunicating air passage and valve chamber between them, there being an opening in one of the plates, a diaphragm valve closing the opening and having its edges clamped between the plates, there being a port in each plate communicating with the valve chamber, a second valve in the valve chamber between said ports formed at least in part of a magnetic metal, and an electro-magnet positioned to effect movement of the second valve to open and close the ports. 55

Signed at Los Angeles, California, this 8 day of January, 1926.
